Filed Aug. 4, 1966, Ser. No. 3,338

Term of patent 14 years

(Cl. D64—10)

FIG. 1.

FIG. 2.

FIG. 3.

FIG. 4.

FIG. 6.

FIG. 5.

FIGURE 1 is an isometric view of a rubber stamp showing our new design, the broken line showing of a wall rod in this view only being merely illustrative of the manner of securing the stamp to a wall;

FIGURE 2 is an elevational view showing the end opposite that seen in FIGURE 1;

FIGURE 3 is a front elevational view thereof;

FIGURE 4 is a rear elevational view thereof;

FIGURE 5 is a top plan view thereof; and

FIGURE 6 is a bottom plan view thereof.

The characteristic features of our design reside in the combination on the rubber stamp disclosed of the specific opening in the handle portion all as shown in solid lines on the drawing, the conventional stamping means at the bottom being shown in dot-dash lines in all the views except FIG. 5.

We claim:

The ornamental design for a rubber stamp or the like, substantially as shown and described.
